UNITED STATES PATENT OFFICE.

WALTER J. COOMBS, OF WOLLASTON, MASSACHUSETTS, ASSIGNOR TO
TUBULAR RIVET & STUD COMPANY, OF BOSTON, MASSACHUSETTS,
A CORPORATION OF MASSACHUSETTS.

LACING HOOK OR STUD SETTING MACHINE.

SPECIFICATION forming part of Letters Patent No. 734,823, dated July 28, 1903.

Application filed December 1, 1902. Serial No. 133,411. (No model.)

To all whom it may concern:

Be it known that I, WALTER J. COOMBS, of Wollaston, in the county of Norfolk and State of Massachusetts, have invented certain new and useful Improvements in Lacing Hook or Stud Setting Machines, of which the following is a specification.

My invention relates to machines for setting lacing hooks or studs, and more especially to a machine in which the studs are separated from a mass and fed automatically to the devices which insert and set them in the material to which they are to be applied. One object of the invention is to provide for a constant supply of studs to the setting devices, and this is accomplished by driving the device which separates the studs from the mass of studs in such a manner that it is continuously operated during the intermittent operation of the setting devices.

A further object of the invention is to provide simple and efficient devices for receiving the individual studs and setting them in the material which will allow the material to be readily and conveniently fed by the operator without any great degree of skill or care on his part. The features by which this object is accomplished, as well as those other features of the invention which contribute to the simplicity and efficiency of the machine, will be set forth in the claims.

The features of invention will be best understood from a detailed description of the machine in which I have embodied them, which machine I have shown in the accompanying drawings, in which—

Figure 1 is a side elevation of the machine. Fig. 2 is a front elevation. Fig. 3 is a partial sectional view through the setting devices. Fig. 4 is a similar view showing the parts in a different position. Fig. 5 is a sectional view on line 5 5, Fig. 3. Fig. 6 is a sectional view on line 6 6, Fig. 3. Fig. 7 is a sectional view on line 7 7, Fig. 5. Fig. 8 is a sectional view on line 8 8, Fig. 1. Fig. 9 is a detail plan view of the setting-plate.

I have embodied the features of my invention in a machine having in many respects the same general construction as the machine

shown in Patent No. 277,985, dated May 22, 1883. In this machine the studs are placed in a hopper and are separated from the mass and directed onto a guideway by a vertically-reciprocating plate, which is operated from the cam-shaft which operates the setting devices. This shaft makes a single revolution to feed and set each stud and then stops and remains at rest until the operator steps upon a treadle and again starts the shaft. If the operator keeps his foot upon the treadle, a number of studs may be set in succession without stopping the shaft. The shaft remains at rest, however, when the setting of the studs is interrupted for the purpose of placing a new piece of material in position or to enable the piece to be properly fed. The operation of the reciprocating plate is interrupted whenever the operation of the setting devices ceases, since the plate is driven from the same cam-shaft. It sometimes happens, therefore, that the supply of studs in the guideway becomes exhausted, necessitating the running of the setting devices idly until the guideway is supplied, thus reducing the capacity and efficiency of the machine. This objection I have overcome by operating the reciprocating plate by a mechanism which may be run without interruption independently of the mechanism for operating the setting devices.

The hopper in which the hooks are placed is indicated at A, and in this hopper is located the vertically-reciprocating plate B for separating the studs from the mass and directing them onto the inclined guideway C. The plate B is carried by a rock-shaft b and is operated by a cam b', which engages a roll carried by a lever b², the upper end of which is connected, by means of a link b³, with the end of an arm b⁴, secured to shaft b. The cam-groove b' is formed in a disk b⁵, to which is secured a gear b⁶, engaged and driven by a gear b⁷, secured to a shaft b⁸. The shaft b⁸ may be continuously driven during the operation of the machine by means of a friction-disk b⁹, Figs. 1 and 8, secured thereto and arranged to engage a friction-disk b¹⁰ on the continuously-rotating driving-pulley D.

The disk b^9 is held in engagement with the disk b^{10} by a spring b^{11} , and so long as the disks are in engagement the cam-disk b^5 is continuously rotated, thereby operating the reciprocating plate B continuously. The operation of the plate B may be stopped at any time by means of a cam-lever b^{12} , the lower end of which is wedge-shaped and is arranged to engage a collar b^{13} on the shaft b^8 and move the shaft longitudinally, thereby disengaging the disks b^9 b^{10} .

In order to avoid breaking or injuring the mechanism in case a stud becomes jammed between the plate B and wall of the hopper so as to interfere with the movement of the plate B, the link b^8 is made in two parts with a spring interposed between them, which yields to allow the movement of lever b^2 when the plate B is stopped. One of these parts consists of a tube b^{14} , connected with the arm b^4 , and the other part consists of a rod b^{15} , sliding in said tube and connected with the lever b^2 . The spring b^{16} is interposed between the end of the tube and a pin b^{17} , which extends through the rod b^{15} and a slot in the tube.

The studs pass from the plate B onto a guide-plate C', and individual studs are separated from the series of studs on the guide and directed into a guide F, which leads to the setting devices, by a separator G. The stud slides down the guide F, with the front or open side of the hook in advance, into position in front of a reciprocating feeding-slide F', by which it is advanced to the setting devices as in the patent referred to. The separator G is operated by a pin g on a disk D', secured to the cam-shaft D², which is arranged to strike the end of a lever g^2 , connected with the separator G by a spring-arm g^3 . The lever g^2 is held in normal position by a leaf-spring g^4 , which bears on a pin g^5 . The feeding-slide F' is operated by a cam-groove f, formed in the disk D' and engaged by a roll on the end of the lever f', which is connected with the slide by a link f^2 and a rod f^3 , which fits in a recess in the end of the slide and bears against a spring f^4 .

The setting devices consist of a spreading and clenching stud or anvil for engaging the tubular shank of the stud after it has been forced through the material and spreading and clenching the same against the material and a setting-plate which engages and supports the head of the shank while it is being forced through the material and clenched. The spreading and clenching anvil H is secured in fixed position in the overhanging arm H', and the setting-plate I is carried on a plunger J, which holds the plate in position to receive the stud from the guide F and then advances toward the anvil H to force the shank of the stud through the material and against the anvil. After the stud has been set in the material the setting-plate is moved back on the plunger to disengage it from the stud, so that the material may be

fed into position to receive the next stud, and the plate is returned to position to receive the next stud as the plunger is retracted. 70 These movements are given to the anvil-plate I by securing it upon a slide i, which is moved in guides formed in a block I², carried by the plunger J. A recess I' is formed in the front of the setting-plate to receive the neck of the 75 stud, and a pocket is formed in the front end of the slide below the plate I to receive the head of the stud. The plate and pocket form a carrier which holds the stud during the setting. When the plunger J is in its lower retracted position, the recess I' and pocket register with the end of the guide F, so that the hook may be carried forward out of the end of the guide and onto the setting-plate, the head being inclosed by the pocket in the slide 80 i except at the back. By thus forming the pocket in the front of the carrying-slide and feeding the studs forward to the pocket—i. e., with the open side of the hook in advance and the neck in the rear—the setting-plate is rigidly supported by the carrying-slide on both sides and at the rear of the pocket, and therefore rigidly and properly supports the end of the stud-shank during the setting.

In order to free the stud from the plate I 95 and the pocket, the slide i is moved back in its guides after the setting operation is completed. This movement is given to the slide by a spring i', Figs. 5 and 6, which is mounted in a recess in the block I² and engages a pin i², secured to the slide and working in a slot i³ in the block. The slide is advanced against the tension of the spring by means of a lever i⁴, pivoted to the block I², the upper end of which engages the slide and the lower 100 end of which is arranged to ride against a fixed pin i⁵ as the plunger J is retracted, and thus rock the lever. The slide is held in its advanced position by means of a spring-catch pawl i⁶, secured to the slide and arranged to 105 engage a shoulder i⁷ on the block, Figs. 3 and 7. As the plunger J is retracted the lever i⁴ rides against pin i⁵, advancing the slide i, so that the pawl i⁶ rides over and engages the shoulder i⁷. The slide is in this advanced 110 position when it receives the stud and remains in this position during the advance of the plunger to set the stud in the material. When the stud is forced against the anvil H, the pawl i⁶ is disengaged from the shoulder i⁷ 115 by means of a pin i⁸, carried in the block I² and arranged to lift the pawl from the shoulder. The pin i⁸ is operated by the movement of the plunger relatively to the block I² when the stud engages anvil H. This movement is provided for by fixing the block I² on a stud I³, mounted in a hole in the plunger and supported on a stiff spring I⁴. The stud I³ is held in position by a pin I⁵ extending through the plunger and through a slot I⁶ in 120 the stud. When the stud is forced against the anvil H with sufficient pressure to set the stud, the spring I⁴ yields to allow the plunger to advance relatively to the block I², 125

thus operating pin i^8 . The friction of the material and stud held between anvil H and plate I holds the slide i in position until the pressure is relieved, when the spring i' quickly moves the slide i back, thus freeing the anvil-plate from the stud, Fig. 4. The material may now be fed while the plunger is being retracted to bring the setting-plate into position to receive the next stud. The stud is retained in position on the anvil-plate as the plunger J advances by a spring-pressed retaining-plunger K , mounted in the block I^2 and having its end shaped to conform to the shape of the head of the stud. The plunger is held in the block and its upward movement limited by a screw k , the end of which plays in slot formed in the side of the pin. When the stud is fed to the anvil-plate by the slide F' , the head of the stud rides onto the end of the pin K and the stud is held in position on the plate until it is properly set in the material. The pin K is of smaller diameter for a part of its length, so that a shoulder is formed thereon which engages a shoulder in the recess in which the pin is mounted when the stud is in setting position. The head of the stud is therefore supported rigidly against movement during the setting, and all danger of bending the stud out of shape during the setting is avoided.

The plunger J is mounted for vertical movement in the frame of the machine and is prevented from rotation by a pin J' , which enters a groove J^2 in the plunger. The lower end of the plunger rests on a bearing-block J^3 on the end of a lever J^4 and is held against said block by a spring J^5 . The lever J^4 is operated to raise and lower the plunger by the disk D' , which is eccentrically mounted on the shaft D^2 and forms a cam for engaging a roll J^6 on the end of the lever. The shaft D^2 is operated from the driving-shaft D^3 through gears D^4 , connecting said shafts. (Shown broken away in Fig. 1.) The shaft D^3 is driven from the driving-pulley D through clutch mechanism similar to that shown in the patent referred to. When the operator presses the treadle L , the guard L' is operated to release the clutch-pawl L^2 , so that it engages one of the teeth on the hub of pulley D and connects said pulley to the shaft D^3 . The shaft D^2 is now rotated, and the guard is held in position by the annular rib L^3 on the disk D' until the shaft D^2 has made a revolution, when the notch in said rib registers with the roll L^4 on the bar L^5 , which carries the guard. The guard is then moved to disengage the clutch-pawl, and roll L^4 enters the notch in rib L^3 and holds the shaft D^2 stationary until the operator again presses the treadle.

What I claim, and desire to secure by Letters Patent, is—

1. A lacing hook or stud setting machine having in combination, a hopper for holding the studs, a separating-plate reciprocating therein, setting devices, means for transfer-

ring the studs from the plate to the setting devices, mechanism for operating the setting devices, a driving-pulley, means for connecting said mechanism with said pulley and automatically disconnecting it therefrom, a cam for operating said separating-plate, a friction-disk connected with said cam to drive the same, and a friction-disk on the driving-pulley for driving said friction-disk, substantially as described. 70

2. A lacing hook or stud setting machine having in combination, an anvil, a reciprocating plunger, a slide carried by the plunger, 80 a pocket in the front end of the slide, a setting-plate covering the pocket and having a recess for the neck of the stud, means for retracting the slide after the setting operation and means for advancing the slide previous 85 to the next setting operation, substantially as described.

3. A lacing hook or stud setting machine having in combination, an anvil, a reciprocating plunger, a stud-carrier supported by 90 the plunger, a setting-plate on the carrier, a spring for retracting the carrier, a catch for holding the carrier in position for setting and means for operating the catch during the setting operation, substantially as described. 95

4. A lacing hook or stud setting machine having in combination, an anvil, a setting-plate and a spring-pressed retainer constructed to hold the stud in position on the plate and to rigidly support the head of the stud 100 during the setting, substantially as described.

5. A lacing hook or stud setting machine having in combination, an anvil, a setting-plate, a spring-pressed plunger for engaging the head of the stud and holding the stud in 105 position on the plate, and means for rigidly supporting the plunger during the setting whereby displacement of the head during the setting is prevented.

6. A lacing hook or stud setting machine 110 having in combination, an anvil, a reciprocating plunger, a block carried by the plunger, a slide in said block, a setting-plate on said slide, a spring for moving said slide back, a catch for holding said slide in position for setting, a lever for advancing the slide and a fixed pin engaged by the lever, substantially as described. 115

7. A lacing hook or stud setting machine having in combination, an anvil, a reciprocating plunger, a block yieldingly supported in said plunger, a slide in said block, a setting-plate on the slide, a spring for moving the slide back, a catch for holding the slide in position for setting, and a pin engaging 125 said catch and the plunger, substantially as described.

In testimony whereof I have affixed my signature in presence of two witnesses.

WALTER J. COOMBS.
